PERMUTATION-LOCK FOR LATCH-LEVERS.

1,229,520.

Specification of Letters Patent. Patented June 12, 1917.

Application filed October 30, 1916. Serial No. 128,532.

To all whom it may concern:

Be it known that I, WARREN J. REAGAN, a citizen of the United States, residing at Admire, in the county of Lyon and State of Kansas, have invented certain new and useful Improvements in Permutation-Locks for Latch-Levers, of which the following is a specification.

This invention relates to an improved lock device and while it is capable of general use, is particularly adapted for use with a brake lever of an automobile and the principal object of the invention is to so construct this device that it may lock the lever or other article in a set position so that unauthorized persons cannot operate and steal the automobile or article, it being necessary to set the combination in order to move the latch to a releasing position.

Another object of the invention is to so construct this lock that the locking mechanism will be contained in the head or hand-grip of the lever, the setting disk being mounted above the head and carried by the latch releasing plunger.

Another object of the invention is to so construct this lever that the latch actuating and locking means will be inclosed therein with the exception of the upper end portion of the releasing plunger or rod and setting disk, the plunger extending above the hand-grip of the lever to permit the combination to be easily set and to further permit the plunger to be easily reached with the thumb in order to move the plunger downwardly after the combination has been set.

Another object of the invention is to so construct this lever that the releasing plunger may be turned without the latch being turned but to prevent the plunger from being moved downwardly excepting when the combination is set.

This invention is illustrated in the accompanying drawings, wherein:—

Figure 1 is a view showing the improved latch lever principally in elevation, the lower portion of the lever being shown in section,

Fig. 2 is a view showing the lever in longitudinal section,

Fig. 3 is an enlarged vertical sectional view through the hand-grip.

Fig. 4 is a transverse sectional view taken along the line 4—4 of Fig. 3.

Fig. 5 is a transverse sectional view taken along the line 5—5 of Fig. 3.

Fig. 6 is a transverse sectional view taken along the line 6—6 of Fig. 3.

Fig. 7 is a transverse sectional view taken along the line 7—7 of Fig. 3.

Fig. 8 is a view similar to Fig. 5 with the locking mechanism scattered thus preventing downward movement of the plunger or rod.

The latch lever is provided with a tubular body 10 having its lower end portion split longitudinally to provide arms which straddle the rack 11 and are pivotally connected with the cross bars 12 of the rack by means of the pivot pin 13. The latching tooth or pawl 14 is positioned beneath the rack bar 11 and is engaged by a spring 15 positioned between the arms of this tubular body and engaging the pivot pin 13 so that the spring will serve to yieldably hold the latching tooth 14 in engagement with the teeth of the rack bar. A yoke 16 or cross bar is slidably mounted upon the reduced end 17 of the plunger 18 and carries hanger rods 19 which extend downwardly through the tubular body 10 upon opposite sides of the rack bar and engage the latching tooth 14 to cause the latching tooth to be moved downwardly against the tension of spring 15 when the plunger 18 is moved downwardly to bring the shoulder 20 into engagement with the cross bar or yoke 16.

The head or hand-grip 21 which is hollow is positioned about the upper end portion of the plunger 18 beneath the plunger head 22 and has its threaded lower end portion engaged by the threaded collar 23 thus rotatably connecting this hand-hold or head with the tubular body. A notch is formed in the threaded lower end portion of this handle 21 to receive the tooth 24 of the sleeve 25 and therefore this sleeve will be connected with the handle. This sleeve 25 rests upon the upper edge of the tubular body thus preventing it from moving into the

body and is engaged by the abutment pin 26 extending through the plunger 18. This provision of the abutment pin 26 prevents the plunger from moving upwardly through the sleeve beyond the position shown in Figs. 2 and 3 and as this sleeve is provided with a bead 27 at its lower end engaged by the handle or hand-grip 21, it will be readily seen that the plunger cannot move upwardly beyond the desired amount. A groove 28 is formed in this sleeve 25 and extends longitudinally through the same so that the rib 29 of the plunger may move downwardly through this groove when the plunger is pressed. The setting disk 30 is mounted upon the plunger above the head 21 and held against rotation upon the plunger by means of the pin 31 fitting into the groove 32 and carries indicating characters as shown in Figs. 1 and 3 which will be positioned with respect to the marks 33 of the head 21 when setting the combination.

Within the head 21 there is provided a setting cup 34 positioned upon the plunger 25 and provided with a neck 35 in which there is provided a longitudinally extending slot to receive the rib 29. This cup is cut out to provide a groove or pocket 36 and is provided with openings 37 and 38 into which will be placed the pins 39 and 40. It is of course understood that as many openings may be provided as desired and that the pins will be removed from the openings in which they are shown and placed in different openings when changing the combination. The upper end portion of the sleeve 25 is reduced to provide the neck 41 having a thickened lower end portion 42. A locking disk 43 is placed about the reduced neck 41 and a larger locking disk 44 is rotatably mounted about the thickened lower portion 42 of this neck, the disk or washer being provided with slots to permit passage of the rib 29 when set in the proper position and being provided with pins 45 and 46 for engagement by the pins 39 and 40 in setting the combination. After the sleeve 25 is put in place, the disks 43 and 44 are placed upon the upper end of the sleeve and the turning cup is then put in place after which the spring 47 is put in place as shown in Figs. 2 and 3 and the pins 48 passed through the plunger to engage the upper end of this spring 47. This spring not only serves to hold the cup in engagement with the upper end of the sleeve 25 but also serves to normally hold the plunger in the raised position shown, the pins 26 and 49 preventing the plunger from moving upwardly beyond the desired amount. By removing the pin 48, the spring 47 will engage the upper end of the hand-grip 21 thus holding the cup in the position shown in Fig. 3 but permitting the plunger to drop with the rib 29 passing into the groove 28. The head or hand grip

21 is then put in place and engaged by the collar 23 and the setting disk 30 is then secured upon the plunger above the head 21 by means of the pin 31. After the head 22 is put in place the lever is ready for use.

When in use, the rack bar is mounted at a convenient point and the latch lever is pivotally connected with the cross bar 12 and the lever mounted as shown. When it is desired to start the automobile it is simply necessary to turn the plunger through the medium of the head 22 until the proper combination has been set through the medium of the disk 30 and the plunger can then be pushed downwardly thus moving the latch 14 to a releasing position and permitting the lever to be swung upon its pivot pin thus releasing the emergency of the automobile. If the pin 48 has been removed, it will of course be necessary to raise the plunger to bring the rib 29 above the sleeve 25 before the plunger can be turned. After the lever has been moved to the desired position, the plunger can be released and the springs 47 and 15 will return the mechanism to the normal position, the locking disk of course remaining in the set position for permitting downward movement of the plunger when desired. Upon leaving the machine, the lever can be moved to set the brake and the plunger can then be turned through the medium of the head 22 thus scattering the combination. It would then be impossible to move the lever without the knowledge of the combination. When again entering the machine, the plunger will be moved and turned first in one direction to set one of the locking disks and then in the opposite direction to set the second disk and then given another turn to bring the tongue 29 into the proper position for passing through the aligned openings in the locking disks and through the groove 28 in the sleeve 25. Of course, it is obvious that this is only one combination which could be used and that each change of combination would require a different series of turns to properly set the combination. The lever is therefore so constructed that only a person knowing the combination can move the same after it has been moved to a set position and the combination scattered. There has further been provided, a lever so constructed that the locking mechanism is positioned in the head or hand-grip 21 where it will be concealed thus preventing tampering with the combination. There has been further provided a locking mechanism for a lever which will be composed of a comparatively few number of parts so constructed that they will not be liable to easily get out of order.

What is claimed is:—

1. A lock of the character described comprising a housing, a plunger passing through

- the housing, a rib extending from the plunger within the housing, a sleeve positioned in the housing about the plunger and held against rotation within the housing and provided with a groove to receive the rib of said plunger, locking disks rotatably carried by said sleeve and provided with cutouts to permit passage of the rib when in alinement with the groove of the sleeve, and a turning cup mounted upon said plunger and held against rotation thereon by said rib, the turning cup being provided with means for engaging the disks to move the disks to a set position when said plunger is rotated. 5
- 15 2. A latch lever comprising a tubular body, a hollow head for the tubular body provided with a notch in its lower end portion, a latch actuating plunger extending through the head and into the tubular body, 20 a sleeve positioned upon the plunger within said head and provided with a tooth fitting into the notch of the head, means for releasably connecting the head with the hollow body, the sleeve being provided with a longitudinally extending groove leading from its passageway, a rib extending from the plunger for passing through the groove of the sleeve when the plunger is moved longitudinally, locking disks rotatably mounted 25 upon the sleeve and provided with grooves permitting passage of the rib through the disks, abutments carried by said disks, a setting cup mounted upon the plunger above the disks and provided with a cutout to receive the rib, and an abutment extending from the setting cup to engage the abutments of the disks and move the disks to a set position when the plunger is rotated in the head. 30
- 35 40 3. A latch lever comprising a tubular body, a hand-grip connected with the tubular body, a plunger passing through the hand-grip and into the tubular body, a latch supported from the lower end portion of said plunger, a rib extending from the plunger within the hand grip, a sleeve loosely mounted upon said plunger and held against rotation within the hand-grip and provided with a groove to receive said rib, locking 45 disks rotatably carried by said sleeve and provided with cutouts to permit passage of the rib when in alinement with the groove of said sleeve, and a turning cup mounted upon said plunger and held against rotation thereon by said rib, the turning cup being provided with means for engaging the disks to move the same to a set position when said plunger is rotated. 50
- 55 4. A latch lever comprising a tubular body, a hollow head for the tubular body provided with a notch in its lower end, a latch actuating plunger extending through the head and into the tubular body, a sleeve 60
- positioned upon the plunger within the head and provided with an outstanding flange engaging the upper end of the tubular body and having a tooth fitting into the notch of the head, a collar rotatably mounted upon the tubular body and in threaded engagement with the lower end of the head, the sleeve being provided with a longitudinally extending groove leading from its passageway, a rib extending from the plunger above the sleeve for passing through the groove thereof when the plunger is moved downwardly, a relatively large locking disk rotatably mounted upon the upper portion of the sleeve and provided with a notch for registering with the groove of the sleeve, a pin extending from the disk, a relatively small disk rotatably mounted upon the sleeve above the large disk and provided with a groove for registering with the groove of the larger disk, a pin extending from the relatively small disk, a cup mounted upon the plunger above the disk and provided with a neck having a slot to receive the rib, pins extending from the cup to engage the pins of the disks, and an indicating disk positioned above the lever head with the plunger slidably passing through the indicating disk, the indicating disk turning with the plunger when the plunger is moved to rotate the cup and set the locking disk. 65
- 70 75 80 85 90 95 100 105 110 115 120 125
5. A latch lever comprising a tubular body, a hand grip connected with the tubular body, an actuating plunger extending through the hand grip and into the tubular body, a cross head slidably mounted upon the lower end portion of the plunger and limited in its sliding movement, a latching tooth, hanger rods carried by the cross head and engaging the latch tooth, a spring positioned beneath the latch tooth and engaging the same to yieldably hold the latch tooth in a raised position, a sleeve loosely mounted upon said plunger within said hand grip and having engagement with the hand grip to prevent independent movement between the sleeve and hand grip, an abutment carried by the plunger beneath the sleeve to limit upward movement of the plunger through the sleeve, a rib extending from the plunger above the sleeve, locking disks rotatably mounted upon the sleeve, a setting cup loosely mounted upon the plunger and held against rotation thereon by said rib, and provided with means for engaging the locking disks to move the same to a set position when said plunger is rotated, a spring positioned about the plunger and engaging the setting cup, and an indicating disk mounted upon the plunger above the hand-grip and rotating with the plunger. 125

an actuating plunger passing through the body and hand grip, a latching tooth, a yoke slidably mounted upon the plunger and having arms engaging the latching tooth, means 5 engaging the latching tooth and yieldably holding the latching tooth in a raised position, and locking means for the plunger.

In testimony whereof I affix my signature in the presence of two witnesses.
